CLOSURE LATCHING ASSEMBLY

Glenn H. Norquist, Jamestown, N. Y.

Application June 23, 1945, Serial No. 601,213

2 Claims. (Cl. 292—240)

1

This invention relates to a closure latching assembly designed and adapted to releasably latch and secure a closure structure to an adjacent fixed structure in a manner to provide a relatively tight seal therebetween.

In accordance with this invention, a highly efficient and economical closure latching assembly is provided comprising a latching rim secured to the fixed structure adjacent the opening which receives the closure member, the closure member being provided with one or more latching devices positioned adjacent the latching rim which may be easily manipulated to and from latched to unlatched position.

This improved closure latching assembly may be associated with either hinged or removable closures of various kinds, with the fixed structure adjacent the closure opening provided with a locking rim designed to cooperate with one or more latching devices fixed to the closure to releasably retain the closure in fixed position. This improved closure latching assembly is particularly adapted for association with containers equipped with a closure cover which must be locked or latched in relatively tight, leak-proof, seating engagement with the container body. By the use of this improved closure latching assembly, the peripheral edge of the closure may be firmly pressed into leak-tight seating engagement with the surrounding closure seat of the container, sufficient pressure being exerted on the closure cover by means of the cooperating cam latches and latching rim to insure the required leak-proof seal.

An object of this invention provides an improved closure latching assembly for releasably securing a movable closure member to a fixed closure seat structure whereby a predetermined seating pressure may be exerted upon the closure member.

Another object of this invention is to provide an improved closure latching assembly comprising one or more latching devices each having a latching cam adapted to be rotated into and out of latching engagement with an adjacent latching rim fixed to the closure seating structure.

A further object of this invention is to provide a container and container closure having a closure latching assembly associated therewith whereby the closure may be secured and locked in substantially leak-tight engagement with the closure seat of the container.

A further object of this invention is to provide an improved latching device which can be inexpensively formed and assembled from stamped

2

metal parts, which is strong and sturdy in construction, substantially fool-proof in operation, and which is adapted to be secured to a closure member in a manner to prevent unauthorized removal thereof when in latching position.

Other objects and advantages of this invention will become apparent as the disclosure proceeds.

Although the characteristic features of this invention will be particularly pointed out in the claims appended hereto, the invention itself, and the manner in which it may be carried out, may be better understood by referring to the following description taken in connection with the accompanying drawings forming a part hereof, in which

Fig. 1 is a top plan view of a container showing a plurality of the improved latching devices associated with the container closure, the latching devices being shown in latching engagement with the latching rim of the container.

Fig. 2 is a side elevational view of the container showing particularly the latching rim associated therewith.

Fig. 3 is an enlarged fragmentary cross sectional view taken vertically through the container and showing particularly one of the latching devices associated with the container closure, as the same appears when viewed along line 3—3 of Fig. 1.

Fig. 4 is another fragmentary cross sectional view taken vertically through the container and the container closure, this view illustrating further details of the closure latching devices, this view being taken along lines 4—4 of Fig. 1.

Fig. 5 is an enlarged fragmentary top elevational view of a corner portion of the container, the container closure and one of the closure latching devices in unlatched position.

Fig. 6 is a top elevational view of the anchor plate which forms one element of the closure latching device.

Fig. 7 is a side edge view of the anchor plate as the same appears when looking in the direction of the arrows 7—7 of Fig. 6.

Fig. 8 is another edge view of the anchor plate as it appears when looking in the direction of the arrows 8—8 of Fig. 6.

Fig. 9 is a top plan view of the cam latch which forms another part of the closure latching device.

Fig. 10 is a side edge view of a cam latch as the same appears when looking in the direction of the arrows 10—10 of Fig. 9.

Fig. 11 is another edge view of the cam latch

as the same appears when looking in the direction of the arrows 11—11 of Fig. 9.

Fig. 12 is a still further edge view of the cam latch as the same appears when looking in the direction of the arrows 12—12 of Fig. 9.

Fig. 13 is an elevational view of the stud pin forming another part of the closure latching device whereby the cam latch shown in Fig. 9 is rotatably secured to the anchor plate shown in Fig. 6.

Fig. 14 is an elevational view of the friction washer which is positioned between the cam latch and anchor plate.

Fig. 15 is a top elevational view of the closure latching device assembled from the parts shown in Fig. 6 to Fig. 14 inclusive, and showing the cam latch rotated to latching position.

Fig. 16 is an edge view of the closure latching device as the same appears when viewed in the direction of the arrows 16—16 of Fig. 15.

Fig. 17 is a top plan view of the fully assembled latching device showing the cam latch rotated to unlatching position.

Fig. 18 is a side elevational view of the latching device as the same appears when viewed in the direction of the arrows 18—18 of Fig. 17.

Fig. 19 is a plan view of a simple form of wrench which may be used to rotate the cam latch when the latching device has been applied to the closure; and

Fig. 20 is a side elevational view of the cam manipulating wrench shown in Fig. 19.

Similar reference characters refer to similar parts throughout the several views of the drawings and specification.

For purposes of illustration, there is shown in Figs. 1 to 5 inclusive the improved latching assembly associated with a box or container which may be said to comprise generally a bottom wall 1, enclosing side walls 2, and a closure cover 3. The closure cover 3 is designed to seat upon the upper end of the enclosing side walls 2 of the container and the closure latching assembly is so constructed and arranged as to releasably lock the closure cover 3 to the enclosing side walls 2 of the container.

The closure latching assembly comprises generally a latching rim *f*, formed of metal or other rigid material which is secured to the enclosing side walls 2 of the container. A plurality of cam latching devices are fixedly secured at selected spaced intervals to the closure cover 3 and so positioned as to releasably engage the latching rim *f*. Each of the cam latching devices comprises generally an anchor plate *a* having a cam latch *c* rotatably secured to the anchor plate by means of a stud pin *b*. The cam latches *c* are arranged to be rotated into and out of latching and locking engagement with the latching rim *f*. A friction washer *d* is positioned between the anchor plate *a* and the cam latch *c* to provide a predetermined frictional resistance to the rotation of the cam latch *c*. The construction and assembly of the latch device is more particularly illustrated in Figs. 6 to 18 inclusive.

The anchor plate, as shown more particularly in Figs. 6, 7, and 8, comprises a relatively flat body section 10 having a downturned lip 11 at one edge thereof adapted to grip the adjacent edge of the cover closure 3. The body section 10 of the anchor plate is provided with a suitable number of spaced holes 12 through which screws may be inserted to secure the anchor plate to the cover closure 3. The body section 10 of the anchor plate is also provided with a centrally

located hole 13 through which the stud pin *b* may be inserted. The anchor plate may also be provided with an upturned lug 14 at one edge thereof to limit the rotating movement of the cam latch, as more particularly described hereafter. The anchor plate can be inexpensively formed as a metal stamping.

The cam latch *c* as shown in Figs. 9 to 12 inclusive, may also be inexpensively made by a metal stamping operation. Cam latch *c* comprises a relatively flat base section 15 having a semi-circular peripheral edge approximately 240° in extent, the ends of the semi-circular edge being joined by a relatively straight edge 17. A cam flange 16 extends upwardly from the semi-circular edge of the base section 15, the upper edge of the cam flange 16 having a cam surface 18 which rises gradually from the low point 19 to a high point 20, spaced approximately 180° to 220° from low point 19. Thus the upper edge of the flange section 16 presents a cam track 18 which rises gradually from the beginning point 19 to a maximum height at point 20. The outer face of the cam flange 16 is a true semi-circle which is equidistantly spaced from pivot hole 21 at the center of the base section 15 through which the stud pin *b* extends.

An abutment lug 22 extends upwardly from the semi-circular edge of the base section 15 and is spaced from the high point terminus 20 of the cam flange 16 to define therebetween what might be termed as notch or recess 23 designed to receive a wrench for manipulating the cam latch, as will be more fully hereinafter described. An abutment lug 24 extends laterally from the base section 15 and is so arranged as to strike the abutment lug 14 associated with the anchor plate *a* so as to limit the rotating movement of the cam latch in a manner more particularly hereinafter described. It will be noted that the bottom surface of the cam latch is relatively flat.

The stud pin *b* shown in perspective in Fig. 13 includes a stem section 30 which is topped by a flared skirt 31. The upper end of the stud pin is provided with a wrench head 32 providing a pivot point for a cam latch manipulating wrench. The stem section 30 of the stud pin *b* has such a diameter as to permit the same to be snugly telescoped through hole 13 in the anchor plate *a* and hole 21 in the cam latch *c*.

The washer *d* shown in Fig. 14 is a flat disc shaped member formed from a material having friction producing surfaces adapted to offer frictional resistance to the rotating movement of the cam latch *c* when rotatably attached by stud pin *b* to the anchor plate *a*. The friction washer *d* has a suitable hole or opening 35 therein through which the stem section 30 of the stud pin *b* may be inserted.

The anchor plate *a*, the cam latch *c*, the stud pin *b* and the friction washer *d* may be quickly and inexpensively assembled to provide the complete cam latch device as shown in Figs. 15 to 18, inclusive. In assembling the latch device, the stud section 30 of the stud pin *b* is telescoped through the stud hole 21 in the base section 15 of the cam latch *c* with the skirt section 31 snugly seating upon the upper face of the base section 15. The friction washer *d* is telescoped over the projecting end of the stud section 30 and the projecting end of the stud section 30 is telescoped through the stud hole 13 in the anchor plate *a*. Finally the projecting end of the stud section 30 is headed over to provide a head portion 34 to securely clamp the anchor plate *a*, the cam latch

c, and the friction washer *d* together in firm assembly.

Figs. 15 and 16 show the fully assembled latch device with the cam latch rotated into latching and locking position. Figs. 17 and 18 show the cam latch as it appears when rotated into unlatched and unlocked position. It will be noted that in the unlocked position, the laterally projecting lug 24 associated with the cam latch abuts the upwardly projecting lug 14 associated with the anchor plate *a* so as to prevent further rotating movement of the cam latch in a counter-clockwise direction as viewed in Fig. 17. In this position it will be noted that the straight edge 17 of the cam latch parallels but does not overlap the lip portion 11 associated with the anchor plate *a*. When the cam latch is in locked position as shown in Figs. 15 and 16, it will be noted that the semi-circular cam flange 16 thereof overhangs and extends beyond the downturned lip 11 of the anchor plate *a*. By rotating the cam latch shown in Fig. 15 in a counter-clockwise direction for a distance of approximately 180°, the straight edge 17 of the cam latch will substantially parallel and not overhang the downturned lip 11 of the anchor plate *a*, thereby placing the cam latch in unlocked or unlatched position. The friction washer *d* interposed between the cam latch *c* and the anchor plate *a* provides a certain frictional resistance to the rotation of the cam latch so that it will not rotate until some fairly substantial rotative force is applied thereto. It will also be noted that the screw holes 12 in the anchor plate are so positioned as to normally underlie the semi-circular section of the cam latch but can be exposed when the cam latch is so rotated as to place its straight edge 17 adjacent the hole to be exposed.

Figs. 1 to 5 inclusive illustrate the manner in which the latching devices may be associated with a container and its closure cover. Fig. 1 more particularly illustrates a plurality of the latching devices arranged in spaced relationship around the perimeter of the closure cover 3. The anchor plates *a* are secured to the closure cover 3 by any suitable securing means, such as screws 36 which are inserted through the screw holes 12 in the anchor plate and threaded into the closure cover 3. The screws 36 may be easily applied before the closure cover 3 is placed in closed position on the container since the latching cam *c* may be readily rotated into various positions to avoid obstruction to the insertion of the screws 36. The downturned lip 11 of each anchor plate is so arranged as to overhang the perimetral edge portion 37 of the closure cover 3.

The latching cams *c* are arranged to cooperate and interlatch with a latching rim *f* secured to the enclosing side walls 2 of the container, which may extend substantially continuously around the upper end of the container. The latching flange *f* comprises more particularly a wall or face section 40 which may be secured as by screws 41 to the adjacent side wall 2 of the container. The face section 40 may also be provided with an in-turned lip 42 at the lower end thereof whereby a secure grip on the side wall of the container is obtained. The upper end of the face section 40 is provided with an in-turned rim section 43 which terminates in a downturned lip 44. The rim section 43 also provides protection to the latch and cover and provides a seat for a superimproved container.

Each of the latching cams *c* is so arranged that the cam flange 16 thereof may be rotated under the downturned lip 44 with the lower edge of the

downturned lip 44 in position to ride over the cam face 18 of the cam flange. Thus it will be appreciated when the cam flanges 16 of the several latching cams *c* have been swung under the downturned lip 44 of the locking flange *f*, the closure cover 3 is securely locked and latched to the container side wall. The closure cover 3 may be unlatched for removal, upon rotating the latching cams *c* in the opposite direction to a point where the straight edge 17 thereof substantially parallels but does not lie beneath the downturned lip 44 of the latching flange *f*, as shown more particularly in Fig. 5. It will be further noted that when the latching cams are in locking position as shown in Figs. 1 and 4, at least two of the securing screws 36 which secure each anchor plate *a* to the closure cover 3, underlie and are concealed by the base section 15 of the latching cam. Thus it will be noted that the anchor plate *a* and the associated latching cam *c* cannot be removed from the closure cover 3 until the closure cover has been first removed from the container. A wire seal 45 or similar sealing device may be connected to each latching cam and the adjacent rim section 43 of the latching rim *f* so that the latched position of the latching cams cannot be disturbed without revealing visible evidence of tampering.

This improved closure latching assembly is particularly adapted and useful for the latching of closure and closure covers associated with structures of various types. By way of illustration only, this closure latching assembly is shown associated with a metal lined plywood container whose bottom wall 1 and enclosing side walls 2 are formed from a base sheet *w* of plywood or like material having a metal liner sheet *m* secured thereto. The bottom wall 1 is provided with a peripheral flange 4 which is secured, as by rivets 5, to a similar flange 6 extending from the lower edge of the side walls 2. The side edges of the side walls 2 are provided with similar laterally extending flanges 7 secured together as by rivet 5. The upper edge of each side wall 2 is provided with a similar laterally extending flange 8 which flares outwardly at approximately 45° to the plane of the side wall 2. The side walls 2 may be suitably braced as by a lower bracing frame 9 and an upper bracing frame 10. The upper bracing frame 10 provides a convenient means for securing the face section 40 of the latching rim *f* thereto as shown more particularly in Figs. 3 and 4. It will be noted by referring to Figs. 3 and 4 that the in-turned lip 42 associated with the face section 40 penetrates into the upper frame 10, thereby providing a secure grip which further secures the locking rim *f* thereto.

The closure cover 3 is likewise provided with an inner metal liner *m* of sheet metal secured to a relatively heavy base member *w'*. A gasket *r* of rubber or like resilient composition is inset into the tapered peripheral edge 50 of the closure cover 3. It will be noted that the gasket *r* seats into a V-shaped notch 51 in the tapered edge 50 of the closure cover 3. By providing such a setting for the gasket, the gasket can be easily shaped and bent around the corners of the closure cover without distorting the gasket. A hole 52 may be made within the gasket, and the outer face 53 of the gasket may be provided with an inclined face so as to snugly seat against the inclined metal surface 54 of the upper side wall flanges 8. It will also be noted that the metal liner sheet *m* of the cover 3 is provided with an upturned peripheral lip 56 which bites into the

gasket *r*, providing a substantially leak-proof seal between the metal liner *m* and the gasket *r*. It will be further appreciated that when downward pressure is exerted on the closure cover *3*, the inclined face *53* of the gasket *r* is pressed into firm sealing contact with the inclined metal surface *54* of the side wall flange *8*, thereby providing a substantially air-tight seal between the side walls of the container and the closure cover *3*.

It will now be appreciated that the improved closure latching assembly comprises latching device arranged to cooperate with a latching rim *f* to exert a firm downward pressure upon the closure when the latching cams *c* are rotated into latching position. Substantially any amount of downward pressure may be exerted on the closure simply by rotating the cam latches *c* to the point where the rising cam flange *16* exerts the desired pressing force against the downturned lip *44* of the fixed latching rim *f*.

A convenient wrench *s* for manipulating the cam latches *c* is shown in Figs. 19 and 20. This cam wrench is provided with a head portion *60* having a hole *61* therein adapted to be telescoped over the head *32* of the stud pin *b*. The head *60* is provided with a neck portion *62* adapted to fit into the recess *23* of the cam latch. The wrench is manipulated by handle portion *63* extending from the neck portion *62*. When the handle portion *63* of the wrench *s*, applied to one of the latch cams as shown in Fig. 1, is rotated in the direction of the arrow *x*, the cam latch is swung into unlatching position, and when swung in the opposite direction, the cam latch is rotated into latching position.

While certain novel features of the invention have been disclosed herein, and are pointed out in the annexed claims, it will be understood that various omissions, substitutions and changes may be made by those skilled in the art without departing from the spirit of the invention.

What is claimed is:

1. An improved latching assembly for releasably securing a closure member to a fixed closure seating structure including in combination, a latching rim adapted to be secured to the seating structure adjacent the closure opening, and a latching device associated with said closure member adapted to cooperate with said latching rim, said latching device including an anchor plate secured to the closure member, a latching cam rotatably secured to said closure member, said latching cam having a semi-circular flange presenting a cam surface adapted to be moved

into and out of latching engagement with said latching rim when said latching cam is rotated; a stud pin rotatably securing said latching cam to said anchor plate, and tool attaching means associated with said latching device operative to facilitate locking and unlocking rotation of said latching cam, said means comprising a pivot head forming a part of said stud pin and a tool receiving notch in the cam flange of said latching cam.

2. An improved closure latching device comprising in combination, an anchor plate adapted to be secured to a closure member to be latched, a latching cam having a semi-circular outer edge and a relatively straight edge extending between the ends of said semi-circular edge, a cam flange extending around said semi-circular edge rising from a low point at one end thereof to a high point at the other end thereof, a friction washer disposed between said anchor plate and said latching cam, a stud pin rotatably securing said latching cam to said anchor plate, and tool attaching means associated with said latching device operative to facilitate locking and unlocking rotation of said latch cam, said means comprising a pivot head forming a part of said stud pin and a tool receiving notch in the cam flange of said latching cam.
